[57] CLAIM

The ornamental design for a closure with lenticular lens insert, as shown.

DESCRIPTION

FIG. 1 is a top plan view of a closure with lenticular lens insert showing my design;

FIG. 2 is a bottom plan view thereof;

FIGS. 3-4 are side elevation views thereof; and,

FIG. 5 is a perspective view thereof.

The characteristic feature of the design resides in a closure having a lenticular lens insert.

The broken line illustration in the Figures illustrates a surface image of the lenticular lens, and is not part of the claimed design.
